(57) **CLAIM**

The ornamental design for a pet treat, as shown and described.

DESCRIPTION

FIG. 1 is a top, front, right perspective view of a pet treat; FIG. 2 is a front elevational view thereof; FIG. 3 is a rear elevational view thereof; FIG. 4 is a top plan view thereof; FIG. 5 is a bottom plan view thereof; FIG. 6 is a right elevational view thereof; FIG. 7 is a left elevational view thereof; FIG. 8 is a bottom, rear, left perspective view thereof; FIG. 9 is an enlarged view as represented in FIG. 2 thereof; FIG. 10 is an enlarged view as represented in FIG. 6 thereof; and, FIG. 11 is an enlarged view as represented in FIG. 4 thereof. The broken lines shown in FIGS. 1-11 illustrate portions of the pet treat that form no part of the claimed design.
